UNITED STATES PATENT OFFICE

2,577,607

AIR SUPPLY SYSTEM FOR WELDERS' HELMETS

Thomas A. Conley, Harrisville, R. I., assignor to
American Optical Company, Southbridge,
Mass., a voluntary association of Massachusetts

Application February 16, 1950, Serial No. 144,497

9 Claims. (Cl. 128—142)

1

This invention relates to improvements in protective devices of the nature of welding helmets and has particular reference to the provision of novel means of supplying filtered air to the wearer of such helmets.

One of the principal objects of the invention is to provide devices of the nature of welding helmets with novel means for supplying filtered air under pressure directly into the breathing zone of the wearer of such helmets.

Another object is to provide a device of the above character wherein the volume of air necessary for maximum efficiency may be supplied at extremely low pressure and with minimum resistance to air flow.

Another object is to provide an arrangement of the above character wherein the danger of causing injurious fumes to be drawn beneath the welding helmet is greatly reduced and substantially completely obviated.

Another object is to provide an arrangement of the above character which obviates the obnoxious noises and turbulences inherent with most prior art devices of the type wherein the air is not baffled during its entry within the helmet.

Another object is to provide a device of the above character which simultaneously functions as a comfortable chin-rest to hold the base of the helmet away from the face of the wearer.

Other objects and advantages of the invention will become apparent from the following description taken in connection with the accompanying drawings. It is apparent that many changes may be made in the details of construction and arrangement of parts shown and described without departing from the spirit of the invention as expressed in the accompanying claims. I, therefore, do not wish to be limited to the exact details of construction and arrangement of parts shown and described as the preferred forms only have been given by way of illustration.

Referring to the drawings:

Fig. 1 is a front elevational view of the device embodying the invention;

Fig. 2 is a fragmentary sectional view taken as on line 2—2 of Fig. 1 and looking in the direction indicated by the arrows;

Fig. 3 is a fragmentary sectional view taken as on line 3—3 of Fig. 1 and looking in the direction indicated by the arrows;

Fig. 4 is a view generally similar to Fig. 3 illustrating a modified form of the invention; and

Fig. 5 is a sectional view taken as on line 5—5 of Fig. 4 and looking in the direction indicated by the arrows.

The providing of air under pressure internally

of welding and similar protective devices and apparatus is well known in the art. In general, such devices have been of the type in which air is supplied to the helmet through a direct line from a compressor or other source of air pressure. Such arrangements have been found to be undesirable because of the difficulty of controlling the pressure of the air supplied to the helmet.

Another undesirable characteristic of such prior art arrangements is that the air supplied to the helmet is supplied at relatively high pressure, usually from 10 to 20 pounds per square inch.

Such high pressure air lines have been found to be undesirable because of the difficulty of controlling the pressure of the air supplied to the helmet.

Another undesirable characteristic of such prior art arrangements is that the air supplied to the helmet is supplied at relatively high pressure, usually from 10 to 20 pounds per square inch.

2

of welding helmets or similar devices is not new in the art. Most prior art arrangements, however, were such that the air was forced under relatively high pressure into the helmet through a direct feeder line from a compressor for the main purpose of reducing the temperature internally of the helmet and also to prevent the entry of injurious fumes, dust, or other foreign matter.

Such direct air lines introduced difficulty such as the forcing of water due to condensation in the lines through the air lines. The forcing of oil or rust particles or other debris through the air lines leading from the compressor, were also hazardous. Another undesirable characteristic was that of the inherent obnoxious noises such as whistling caused by air turbulences which were created by such direct air lines. In many instances in the past, there was also the danger of creating a "Venturi" action with the danger of causing injurious fumes to be sucked internally of the helmet and into the breathing zone of the wearer.

The present invention, therefore, is directed particularly to the provision of novel means and methods of supplying filtered air directly to the breathing zone of the operator which not only eliminates the presence of water due to condensation, but prevents oil, rust particles or other debris from the air lines from being directed to the breathing zone and further provides an arrangement whereby the prior art obnoxious noises are eliminated and substantially all danger of drawing injurious fumes internally of the helmet are obviated. A further feature of the invention resides in the provision of a device of the above character which requires a relatively low air pressure and which will simultaneously function as exceedingly comfortable chin-rest means for retaining the shape of the helmet in desired spaced relation and which will also function to block the entry of fumes into the bottom of the helmet. Another feature is that of providing a device of the above character which is exceedingly simple and inexpensive in nature and light in weight.

Referring more particularly to the drawings wherein like characters of reference designate like parts throughout the several views, the device embodying the invention comprises a face shield 4 formed of relatively stiff shock and impact resisting material having a suitable window 5 therein through which a relatively wide range of vision is afforded the wearer. The main shield portion 4 is supported on the head of the wearer by a suitable headband arrangement (not shown) of conventional design.

Internally of the shield and in the vicinity of

the chin-rest of the wearer, the device to which the invention is more particularly directed comprises a pair of strips 7 and 8 of material substantially the same as that used in forming the main shield portion 4 which material may be of suitable fiber, compressed paper or similar means. The strips 7 and 8 are positioned in overlapping relation with each other adjacent the free ends thereof and are pivotally connected to the main shield 4 by suitable pivot means 9. The strip 7 is looped forwardly about a radius which is less than that of the curvature of the front portion of the main shield 4, as shown best in Fig. 3, whereby it will be slightly spaced from said shield for relatively free pivotal movement. The strip 8, as it extends forwardly of the pivots 9, is spaced with respect to the strip 7 as it progresses forwardly and is provided with an intermediate portion 10 located at a considerably spaced relation with respect to the intermediate portion 11 of the strip 7. In between the said intermediate portions 10 and 11, there is provided an oval shaped strip 12 formed of material similar to that of strips 7 and 8 and to substantially the same width as said strips having its ends 13 and 14 secured in overlapping relation with each other by suitable rivets or the like 15. The longitudinal sides of the oval shaped strip 12 are shaped substantially to the same shape as the intermediate portions 10 and 11. They are held in relatively intimate relation by suitable rivets or the like 16. In the end of the oval shaped member 12 having the overlapping portions 13 and 14, there is formed an opening through which a suitable air line 17 is extended. This may be in the form of rubber tubing or other suitable means.

The assembly, comprising the intermediate portions 10 and 11 and the oval shaped portion 12 therebetween, is provided with a suitable covering 18 of felt or other desirable filtering material of a thickness controlled according to the speed of air flow desired therethrough and according to the pressure desired in the air line 17.

The oval shaped portion 12 and the covering of felt material 18 form a chamber 19 into which the air from the air line 17 is directed. The ends 20 and 21 constitute the end walls of the chamber while the felt covering which overlies the upper and lower open sides of the oval shaped strip 12 constitute the upper and lower walls 22 and 23 respectively of the chamber.

The air line 17 is connected with a suitable air compressor whereby air may be directed under pressure into the chamber 19 and forced through the upper and lower walls 22 and 23. This causes a clean flow of air directly to the breathing zone of the wearer while simultaneously causing a flow of air in a direction outwardly of the lower side or bottom of the helmet for preventing the formation of a "Venturi" action whereby injurious fumes, dust or other foreign matter may be drawn internally of the helmet.

The strips 7 and 8 and the oval shaped portion 12 are formed relatively resilient and they function cooperatively with the felt covering 18 to provide a relatively comfortable and efficient chin-rest means for retaining the front of the helmet in desired spaced relation with the face of the wearer. Suitable adjustments whereby the filter chamber 19 may be located in proper relation with the wearer is provided by the pivots 9.

The felt or other suitable material 18 is such that when air is forced therethrough under pres-

sure there will be little, if any, noise created thereby.

While the device functions as extremely efficient filtering means of the above character, it also provides means for reducing the temperature internally of the face shield to a comfortable and desirable degree.

It is to be understood that the felt covering 18 is so formed as to have a relatively intimate fit about the oval shaped member 12 in order to form a suitable closed chamber 19. The felt covering may comprise a plurality of sections secured in stitched relation with each other along their meeting edges 24 or otherwise joined in sealed relation with each other, as illustrated best in Fig. 2.

In Figs. 4 and 5, there is illustrated a modified form of the invention which comprises a single strip of material 25 pivotally connected adjacent its opposed ends as illustrated at 26 to the face shield 27. The strip 25 is formed of pressed paper, fiber or other suitable relatively stiff and yet flexible material. The said strip 25 has a strip 28 having substantially the same characteristics as said strip 25 secured thereto. The said strip 28 has its ends 29 looped and turned forwardly and secured to said strip 25 by suitable rivets or the like 30. Intermediate the forwardly curving portions of said strip 25 and the strip 28, there is positioned a looped strip 31 having its ends 32 secured in overlapped relation with each other and to the intermediate portion of the strip 25 as by the rivet or the like 33. The said member 31 functions as spacer means for retaining the intermediate portions of the strip 25 and the strip 28 in spaced relation with each other. One of the looped ends 29 of the strip 28 is provided with an opening through which a suitable air line 34 is extended. The looped strips 28 and 31 are provided with a covering of suitable filtering material such as felt, paper or other desirable filtering means 35 whereby the said looped strip 28 and the forwardly curving portion of the strip 25 will form an air chamber 36 into which air may be directed through to the air line 34. The strip 31, as shown in Figs. 4 and 5, is of less width than the strips 25 and 28 and the air, therefore, is free to pass throughout the length of the chamber 36 through the spaces 37 between said felt filter covering and the upper and lower edges of the strip 31. The felt covering or filtering material 35 may be formed of a plurality of sections joined along their longitudinal edges 38 by stitching or other suitable means. The said looped strip 31 functions as a chin-rest or spacer means for retaining the shield in proper spaced relation with the face while the air filter, in this instance, will function in a manner similar to the previously described filter, that is, it will not only prevent entrance of injurious fumes or the like beneath the face shield but will also supply filtered air directly to the breathing zone of the wearer.

From the foregoing description, it will be seen that simple, efficient and economical means and methods have been provided for accomplishing all of the objects and advantages of the invention.

Having described my invention, I claim:

1. In a device of the character described embodying a face shield, a pair of spaced supports connected to each other adjacent the opposed ends thereof, one of said supports being pivotally connected adjacent its opposed ends to the shield internally thereof, an oval shaped member fitted between said supports, an air line extending within said oval shaped member, and filtering

material overlying the opposed open sides of the oval shaped member and functioning cooperatively with said member to form a chamber into which air is directed by the air line.

2. In a device of the character described embodying a face shield, a pair of supports having arcuately shaped intermediate portions joined with each other adjacent their opposed ends, one of said supports being pivotally connected, adjacent its opposed ends, internally of the shield, filtering material overlying the opposed open sides of said pair of supports throughout the major portion thereof and means for directing a flow of air within said spaced supports and the filtering material.

3. In a device of the character described comprising a face shield, a pair of relatively thin strips of resilient material joined with each other with the major portion thereof in spaced relation with each other, one of said strips being pivotally connected adjacent its opposed ends internally of the shield, means formed of resilient material positioned between said spaced strips and forming spaced wall portions extending transversely of said spaced strips, one of said wall portions having an opening therein, an air line extending through said opening, and filtering material overlying the opposed open sides of said strips and said spaced wall portions to form a chamber into which the air is directed.

4. In a device of the character described comprising a face shield, a pair of spaced supports connected to each other, one of said supports being pivotally connected adjacent its opposed ends internally of the shield, filtering material overlying the opposed open sides of the spaced supports and an air line for directing air between said supports and the filtering material.

5. In a device of the character described comprising a face shield, a pair of supports formed of relatively thin resilient material, said supports being joined with each other adjacent the opposed ends thereof in such a manner as to cause the intermediate portions of said strips to be spaced relative to each other, a relatively thin strip of resilient material having its opposed ends secured in overlapping relation with each other with said strip lying between said first mentioned strips and secured to at least one thereof, said strip having its ends secured in overlapping relation having an opening in the side wall thereof, filtering material wrapped around said strips and having its meeting ends secured together to form a casing of filtering material surrounding said strips and means for directing a flow of air through said openings and into the spaced strips beneath the filtering material.

6. In a device of the character described comprising a face shield, a pair of supports pivotally

connected adjacent one end thereof to said shield and having their intermediate portions in spaced relation with each other, an oval shaped strip fitted between said supports adjacent the front 5 of the shield and internally thereof, an air line extending within said oval shaped member and a covering of suitable filtering material extending about said supports and oval shaped member to function cooperatively with said oval shaped member to form a chamber with the sides of the oval shaped member functioning as the end walls of the chamber.

7. In a device of the character described comprising a face shield, a strip of relatively thin 15 ribbon-like material pivotally connected adjacent its opposed ends internally of the face shield, a second strip of ribbon-like material having looped end portions secured adjacent its free ends to the first ribbon-like strip at a position 20 spaced from the respective pivots with said looped ends causing the major portion of said second strip to be spaced relative to the first strip, filtering material overlying the opposed open sides of said respective strips and means for directing 25 a flow of air between said strips beneath the filtering material.

8. In a device of the character described comprising a face shield, a pair of spaced supports secured to each other, one of said supports having connection means adjacent its opposed ends 30 for connection internally of the shield, filtering material overlying the opposed open sides of the spaced supports and means for directing a flow of air between said supports and the filtering material.

9. In a device of the character described comprising a face shield, a pair of supports formed of relatively thin strips of resilient material secured to each other with an intermediate portion 40 thereof in spaced relation, one of said supports having means adjacent its opposed ends for connection internally of the face shield, filtering material overlying the opposed open sides of the spaced intermediate portions of said supports, 45 and means for directing a flow of air between said supports and the filtering material.
